UNITED STATES PATENT OFFICE.

LEWIS L. SCOTT, OF ST. LOUIS, MISSOURI, ASSIGNOR TO STANDARD ENGINEERING COMPANY, OF ST. LOUIS, MISSOURI, A CORPORATION OF MISSOURI.

THROTTLE-CONTROLLING APPARATUS.

4,343,750.

Specification of Letters Patent. Patented June 15, 1920.

Application filed May 9, 1919. Serial No. 235,838.

To all whom it may concern:

Be it known that I, Lewis L. Scott, a citizen of the United States, residing in the city of St. Louis and State of Missouri, have invented new and useful Improvements in Throttle-Controlling Apparatus, of which the following is a specification.

10 The invention relates to automobile engines, and particularly to means for controlling the throttle of the engine. It has been found that in an emergency, in driving a car a driver under nervous tension is apt to grab the steering wheel with both hands. On this account he may neglect to close the throttle, 15 though he may have sufficient presence of mind to apply the brake with his foot.

20 The general object of the present invention is to provide means whereby the throttle will become automatically closed when the 25 brake is applied. More specifically, the invention may include a holding device, the release of which is effected through the application of the brake, thereby permitting the throttle valve to close.

25 Further objects of the invention will appear hereinafter.

30 The invention consists in the general combination of parts and in the features of said parts hereinafter described, all of which contribute to produce an efficient throttle control for automobile engines.

35 A preferred embodiment of my invention will be particularly described in the following specification, while the broad scope of my invention will be pointed out in the appended claims.

In the drawing, which fully illustrates a preferred embodiment of my invention,

40 Figure 1 is a side elevation of an automobile to which the invention is applied;

45 Fig. 2 is a side elevation in detail showing the manner of mounting my controlling device when associated with the steering post of the car or automobile;

50 Fig. 3 is a section taken about on the line 3—3 of Fig. 2, certain parts being broken away and shown in elevation;

55 Fig. 4 is an elevation showing the forward side of the steering post, and further illustrating the details of my improvements;

60 Fig. 5 is a cross-section upon an enlarged scale taken about on the line 5—5 of Fig. 3; and

Fig. 6 is a side elevation broken away, and shown partly in section illustrating the 55 throttle valve.

In Fig. 1, which illustrates the automobile to which my invention has been applied, 1 represents the boiler in which steam is generated for driving the engine, (not illustrated). On the side of this boiler or at any other convenient point, a throttle valve 2 is provided. The automobile is provided with a steering post 3 of any suitable construction, the lower end of which controls the steering gear including drag-links 4 which connect with the steering knuckles adjacent the forward hubs 5.

I provide means for opening the throttle valve which may be associated with the steering post so as to be within convenient reach of the driver of the car. The controlling member for the throttle valve is a hand-operated lever 6 which is attached rigidly to the upper end of a rotary spindle 7, rotatably mounted in a collar 8 near the upper end of the steering post, see Fig. 2. Any suitable connection may be employed for imparting movement from this spindle 7 to open or close the throttle valve 2. In order to accomplish this, the lower end of the spindle may be provided with an arm 10 to which a link 11 is attached, the other end of said link being pivotally secured to the stem 12 of the throttle valve, see Fig. 6. This stem extends 85 into the throttle valve through one end and carries a valve head 13 which closes against a seat 14.

80 I provide means for closing the throttle which is immediately brought into operation by the actuation of the brake-controlling member, but which is so constructed that it does necessarily depend for its action, even in degree, upon a complete movement of the brake controlling member. For 85 example, the throttle closing means may close the throttle completely if the brake controlling member is actuated at all. For this purpose, I prefer to provide means for holding the valve in the open position in 100 which it has been set by the hand-operated lever 6, and I control this holding means automatically by the operation of the brake so that when the brake is applied, the throttle valve is permitted to close automatically. 105 In order to accomplish this, I provide a

gripping device 15, see Figs. 2 and 3. This gripping device is preferably in the form of a friction-clamp located at an intermediate point on the length of the steering post, and comprising separable jaws including a jaw 17 which may be formed on a fixed bracket 16, and a movable jaw 18 which is preferably attached to the fixed jaw on a pivot-pin 19. These jaws 17 and 18 are formed with half-round recesses or sockets 20 which co-operate to form a substantially cylindrical socket through which the spindle 7 passes.

In order to increase the holding power of the gripping device, I prefer to increase the virtual diameter of the spindle at this point by providing the same with a rotary part in the form of an enlarged head or collar 21 rigidly attached to it by a cotter pin 22, see Fig. 3. This collar 21 fits nicely into the space between the sockets 20 of the two jaws, so that when these jaws are pressed together, they will exert a considerable gripping force operating to hold the spindle against rotation. The jaws are normally pressed toward each other by any suitable spring-actuated means, such as a spring 23, disposed on the projecting end of a bolt 24 passing through the jaws.

Means is provided which will operate to separate the jaws 17 and 18 automatically when the movement is made which will apply the brake. To accomplish this, I form the ends of the jaws into half-round sockets 25, see Fig. 3, which co-operate to form the complete cam socket 26, in which an oblong or oval cam 27 is located. The axis of rotation of this cam coincides with the longitudinal axis of the cam socket 26. The cam 27 may be secured to the end of a wrist 29 operating as the pivot point of a short lever 30, said wrist being rotatably mounted in a bearing formed in a suitable arm 31 on the bracket 16. A connection is made from the brake-controlling member to this lever 30 so that when the brake is applied, the gripping device is released automatically, thereby permitting the valve to close. To this end, the automobile may be provided with any suitable braking mechanism such as a brake band 32 on the hub of the rear wheel 33, which brake band is actuated in any suitable manner by a link 34, the forward end of which is attached to a brake-controlling member in the form of a foot lever 35 pivotally supported at 36, the upper end of said lever having a return bend carrying a foot plate 37. This foot lever 35 is connected by an adjustable link 38 with the lever 30.

66 The lower end of the spindle is rotatable in a bracket 16 fixed to the steering post.

Referring again to the throttle valve, it should be said that the live steam is admitted to the valve through a nipple indi-

cated at 39, see Fig. 6, through which the steam flows into a steam-chest 40 adjacent to the valve head 13. Pressure means is employed tending to close the valve. In the present instance this pressure means is the steam in the valve chest. The valve is opened by moving the valve head inwardly into the steam-chest 40, and hence the valve is normally held on its seat by the steam pressure.

The cam 27 is normally disposed with its longitudinal axis at right angles to the position it occupies in Fig. 5, at which time the ends of the cam lie in the gaps 27 between the jaws.

In the operation of the valve, the force exerted by the lever 6 will exert a thrust in the valve stem 13 which will lift the valve 13 off its seat, and permit the steam to pass the valve and flow toward the engine through the pipe connection 11. After the valve has been set in its open position it is held in its open position by the gripping device 15 until released.

The brake 32 is applied by moving the brake lever 35 forward in the usual manner. This exerts a thrust in the link 38, and produces a slight rocking movement in the wrist 29 which rotates the cam 27 toward the position in which it is indicated in Fig. 5. This movement of the cam will separate the jaws of the gripping device 15, whereupon the steam pressure exerted on the outer face of the valve head will cause the valve to close instantly, thereby shutting off the flow of steam to the engine.

One of the advantages of my apparatus arises from the fact that it is constructed in such a way that the throttle valve is, in a sense, independent of the movement that applies the brake, that is to say, the apparatus operates to close the throttle whether the brake is completely applied or not. For this reason the closing of the throttle valve is not affected in any way by a faulty adjustment of the brake. This is important, because, even if the brake were so adjusted that a very slight movement of the brake lever would suffice to apply the brake, nevertheless this movement would be sufficient to effect the complete closing of the throttle. In other words, it is the movement to apply the brake that effects the closing of the throttle and therefore the degree of closing of the throttle does not depend upon the degree of application of the brake. The first part of the movement of the brake-controlling member effects the closing of the throttle.

It is understood that the embodiment of the invention described herein is only one of the many embodiments this invention may take, and I do not wish to be limited in the practice of my invention, nor in my

claims, to the particular embodiment set forth.

What I claim and desire to secure by Letters Patent is:—

- 5 1. In a controlling apparatus for an automobile engine, the combination of a throttle valve, means for opening said valve, a brake-controlling member for applying the brake, means for closing the throttle valve, and 10 means for effecting the operation of said last named means when said brake-controlling means is actuated.
2. In a controlling apparatus for an automobile engine, the combination of a throttle valve, a hand-actuated member for opening 15 said valve, holding means for holding said valve open, means for closing the valve, a brake for the automobile, and automatic means for releasing said holding means 20 when the brake is actuated, to permit the valve to close.
3. In a controlling apparatus for an automobile engine, the combination of a throttle valve, a hand-actuated member for setting 25 said valve in an open position, holding means coöperating with said hand-actuated member to hold the valve in the open position in which it is set, means for closing the valve, a brake, and a foot-operated member 30 for controlling the brake, connected with said holding means and operating to release said holding means, to permit the valve to close when the brake is applied.
4. In a controlling apparatus for an automobile engine, the combination of a throttle valve, pressure means tending to close said valve, a hand-actuated member for setting 35 said valve in its open position, holding means operating to hold said hand-actuated member in a fixed position after the valve has been set by hand, a brake-controlling member, and means connecting said brake-controlling member with said holding means to actuate said holding means to release the 40 hand-actuated member, and thereby permit the valve to close.
5. In a controlling apparatus for an automobile engine, the combination of a throttle valve, means for setting said valve in an 45 open position, said means including a member mounted to rotate as the valve is set in its open position, a gripper device operating to engage said rotary member to hold the valve in the position in which it is set, 50 a brake for the automobile, a brake-controlling member for applying the brake, and a connection from said brake-controlling member to said gripper device for releasing the same to permit the valve to close.
- 60 6. In a controlling apparatus for an automobile engine, the combination of a throttle valve, means tending to close said valve, hand-actuated means for setting said valve in its open position including a rotary part 65 mounted to rotate in setting the valve in its open position, holding means in the form of a clamp for gripping said rotary part to hold the valve in the open position in which it is set, a brake, a brake-controlling member, and means connecting said brake-controlling member with said clamp for opening said clamp to permit the valve to close.
7. In a controlling apparatus for an automobile engine, the combination of a 70 throttle valve, a spindle connected with said valve for opening the same, holding means for holding said spindle against rotation after the valve is set in its open position, a brake, a brake-controlling member, and 75 means connecting said brake-controlling member with said holding means for releasing said holding means to permit the valve to close when the brake is applied.
8. In a controlling apparatus for an automobile engine, the combination of a throttle valve, pressure means tending to close 80 said valve, hand-actuated means including a spindle for setting said valve in its open position, said spindle having a rotary head, a friction clamp engaging said rotary head to hold the valve in the open position in which it is set, a brake-controlling member, and means connecting said brake-controlling member with said clamp to release the 85 clamp when the brake is applied and thereby permit the valve to close.
9. In a controlling apparatus for an automobile engine, the combination of a throttle valve, hand-actuated means for setting 90 said valve in its open position, spring actuating means for holding said last named means to maintain the valve in its open position, a brake, a brake-controlling member for actuating said brake, and means actuated by said brake-controlling member 95 for releasing said spring-actuated means to permit the valve to close.
10. In a controlling apparatus for an automobile engine, the combination of a throttle valve, valve-controlling means for setting 100 said valve in its open position, a spring-actuated clamp for holding said last named means to maintain the valve in its open position, a brake, a brake-controlling member for actuating said brake, and a cam 105 actuated by said brake-controlling member for opening said clamp to release said valve-controlling means, and thereby permit the valve to close.
11. In a controlling apparatus for an automobile engine, the combination of a throttle valve, a steering post, means mounted on 110 said steering post for setting the throttle valve in an open position, a gripper device 115 coöperating with said last named means for holding the same to maintain the valve in its open position, a brake, a brake-controlling 120 member for actuating said brake, and a cam actuated by said brake-controlling member for opening said clamp to release said valve-controlling means, and thereby permit the valve to close.
12. In a controlling apparatus for an automobile engine, the combination of a throttle valve, a steering post, means mounted on 125 said steering post for setting the throttle valve in an open position, a gripper device coöperating with said last named means for holding the same to maintain the valve in its open position, a brake, a brake-controlling

ling member for actuating said brake, and means connecting said brake-controlling member with said gripper device for actuating said gripper device to release said valve controlling means, and thereby permit the valve to close.

12. In a controlling apparatus for an automobile engine, the combination of a throttle valve, a brake, a brake-controlling mem-

ber for actuating said brake, and means for effecting the closing of the throttle, actuated by the first part of the movement of the brake-controlling member in applying the brake.

In testimony whereof, I have hereunto set my hand.

LEWIS L. SCOTT.
